UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed September 7, 1928. Serial No. 304,478.

This invention relates to clips for holding labels and other small work-pieces in typing position on a platen, especially a platen of small diameter, such as is used in portable typewriting machines.

It is an object of the invention to facilitate the insertion of the work-piece and the gagging thereof, and to improve the means for holding the work-piece fast against the platen, and to provide for convenient typing close to all the edges of the work-piece.

In the preferred form of the invention the sheet-metal shell-like card-holder is self-clasping upon the cylindrical body of the platen. For this purpose the card-holder may have a spring-body which extends a little more than half way around the platen to give it the self-clasping effect, although certain features of the invention are not limited to this type of body.

By means of a series of inverted U-shaped incisions, adjacent one longitudinal edge portion of the shell, there are provided a series of tongues enclosed by the shell for clasping the platen, and a work-clip which is formed along one entire longitudinal edge of the device. The work-clip is supported upon bars which extend from the clip to the body of the device, said bars alternating with said tongues. Said work-clip is offset or spaced a little away from the platen, while the tongues tightly clasp the platen.

After the device is placed in position upon the platen, the bottom edge of the work is inserted downwardly between the clip and the platen, and rests upon the tips of said tongues, which thus form a bottom gage for the work. The tongue-tips are provided with indentations or short raised ribs, to give depth and improve the efficiency of the gages. The platen is then rolled backwardly, together with the card-holder and the card or label, and the bottom rolls which usually run upon the platen will now run upon the card-holder, and will press upon said bars, thereby causing the clip to clasp the label firmly against the platen. To aid in this rolling operation, the bars are formed with longitudinal ribs, which project above the body of the device, so as to be engaged by said bottom rollers. The

clip is held with exceptional firmness to the platen, the grip thereon not being dependent upon the rigidity of the weak body of the card-holder, so that the label is held much more firmly than has been practicable heretofore, and the work is more accurately gaged upon the platen.

One-piece label-holding devices are usually effective because of the resiliency of their spring-tempered bodies. Such devices are not suitable to withstand severe usage or abuse, since their thin bodies can be easily bent so as to destroy the accurately-gaged tension required for properly gripping the work-pieces. Also, such devices require the use of both hands of the operator in using them, since the resilient holder must be held released with one hand while the work-piece is inserted with the other hand, and this usually slows down the speed of the operator.

The work-pieces may be readily inserted with one hand between the platen and the label-holder when the latter is in work-receiving position, and be clamped automatically upon bringing the work-piece to typing position.

The body-portion and integral forwardly-extending fingers are made from a single piece of spring-tempered sheet-metal, and are curved to clasp the platen closely. The label-gripping member is disposed in advance from the fingers and is carried by members which extend rearwardly between the fingers, and are integrally and flexibly joined to the body-portion. The label-gripping member, when in a work-receiving position, is normally disposed far enough away from the platen to permit a work-piece to be readily front-inserted therebetween. Then the platen is rotated rearwardly to bring the label to typing position, and the label-gripping member carrying members are engaged by the lower feed-rolls and the label-gripping member is pressed firmly against the label. When the label is typed, the platen is rotated ahead to bring the label-holder to label-receiving position, and the typed label is automatically released by the gripping member and may be conveniently removed.

The integral, lengthwise, radially-project-

ing ribs in the movable members which carry the label-gripping member secure an effective coaction of the lower feed-rolls and the label-holder, and also make the movable members 5 transmit more of the pressure of the feed-rolls to the label-gripping member.

Other features and advantages will hereinafter appear.

In the accompanying drawings,

10 Figure 1 is a fragmentary cross-sectional view, front to rear, through the platen-carriage of an Underwood portable typewriting machine having my invention applied thereto. In this view the label-holder is 15 shown in work-receiving position.

Figure 2 is a view similar to Figure 1, the label-holder being shown in effective label-holding position, and the label being shown in typing position.

20 Figure 3 is a fragmentary perspective view of the structure shown in Figure 1.

Figure 4 is an end view from the left side, of the label-holder of my invention.

25 Figure 5 is a view illustrating how my label-holder may be easily removed from the platen.

The present invention is illustrated as applied to an Underwood portable typewriting machine in which types 10 strike against a 30 platen 11 supported in a laterally-movable platen-carriage 12 which carries a usual line-finder scale 13. For inserting work-sheets from the rear around the platen, a usual rear paper-table 14 is provided which terminates 35 in a flexible front apron 15 on whose forward extremity may be supported a usual paper-scale 16 whose upper edge is disposed a short distance from the surface of the platen.

Lower feed-rolls 17 may be carried as usual 40 by the apron 15, and springs 18, supported on the platen-carriage 12, are employed in a well-known way to press upwardly against the apron, and are effective to hold the feed-rolls 17 firmly against the platen.

45 A label-holder, generally designated as 20, is made of thin spring-tempered sheet-metal, and is provided with a curved rear body-portion 21 and integral fingers 22 which extend forwardly from the body 21 and are 50 spaced away from each other for a purpose to presently appear. The peripheral distance from the rear edge of the body 21 to the forward end of a finger 22 is slightly more than one-half of the periphery of the 55 platen 11. The curve of the body 21 and fingers 22 is made slightly smaller in radius than the curve of the platen, and the holder 20 may be easily opened or spread to engage around the platen, and will clasp the same 60 securely.

Positioned slightly in advance of the front end of the fingers 22 is a laterally-disposed label-gripping member 23 which is carried on the forward ends of narrow webs or bars 24, 65 hereinafter called label-gripping carriers,

which are integrally joined to the member 23 and which extend rearwardly to be integrally and flexibly joined to the body 21. One label-gripper carrier is disposed between each two adjacent fingers 22, the latter being 70 spaced away from each other slightly more than the width of the carrier. A carrier 24 may also be disposed at each side of the row of fingers 22.

For a purpose to presently appear, each 75 label-gripper carrier 24 is formed with an outwardly, i. e. radially-projecting, lengthwise bead or rib 25 which extends from its forward end adjacent the label-gripper member 23 rearwardly, and terminates adjacent 80 the junction of the carriers 24 and the flexible body 21. It will be noted (see Figure 3) that the slots 26-27 which partly surround the fingers 22, terminate substantially in line with the ribs 25. This construction, while stiffening the label-gripper carriers 24, will also 85 permit the carriers to be readily swung about their flexible junctions with the body 21.

When detached from the platen (Figure 4), the label-gripper 23 and the carriers 24 are 90 disposed outwardly, i. e. in advance of the fingers 22, a short distance. Also, when the holder 20 is in work-receiving position, clasping the platen (Figure 2), the inner face of the label-gripper 23 is disposed a short distance 95 in front of the surface of the platen parallel thereto, whereby a label 30 may be readily inserted between the platen and the gripper. To facilitate inserting the label, an upper or leading edge 31 of the label-gripper may be beveled away from the platen. For aligning the label 30, short outwardly-projecting beads 32 are formed in the end of each finger 22 for engaging the lower edge of the label. In Figure 1 position the front 100 extremity of each bead 32 extends forwardly beyond the inner face of the label-gripper 23 and serves to prevent the label from slipping down between the gripper 23 and the fingers 22, which would often occur if the 105 beads were not provided.

A side-edge gage for laterally positioning each of a series of labels 30 may be provided by moving a usual left-hand upper feed-roll 33 along a lateral shaft 34 to proper position relative to the label-holder, the shaft being supported in the usual manner for carrying the feed-roll.

After inserting and gaging a label 30, when the platen is in work-receiving position as illustrated in Figures 1 and 3, the platen may be reversely rotated by a usual finger-wheel, not shown, until the first line of writing is brought to the printing line, which may be determined by the line-finder scale 13. A usual curved work-guide finger 36 on the line-finder scale presses the label 30 against the platen at the printing point. When the label is in typing position, the lower portions of the rib 25 are engaged by the lower feed-

rolls 17, the stiff label-gripper carriers 24 are swung toward the platen, and the label-gripper 23 is pressed firmly against the label. It will be noted that the lengths of the label-gripper carriers 24 and the rib 25 are such that the rear ends of the ribs pass under the feed-rolls 17 before the bottom-edge portion of the label 30 is disposed at the printing line.

When a label 30 has been typed, the platen 10 may be rotated ahead to bring it to work-receiving position, whereupon the feed-rolls will ride off the ribs 25, and the label-gripper will automatically be swung forward by spring-tension and will release the label 30, 15 which may be quickly and safely removed without danger of tearing.

According to one method of detaching the label-holder, the platen, after being moved to its leftmost position, is rotated backwardly, 20 as indicated by arrow (see Figure 5), until the bottom edge of the body 21 engages the upper edge of the movable front scale, which, by the operator's finger, is pressed against the platen. A slight additional turn given to the 25 platen 11 will cause the holder to smoothly slip off the platen without excessive manual force being applied, the yielding fingers 22 not offering excessive resistance.

Variations may be resorted to within the 30 scope of the invention, and portions of the improvements may be used without others.

Having thus described my invention, I claim:

1. The combination with a typewriting machine platen, of a label-holder including a sheet-like resilient body curved for engagement around said platen, a label-gripper member disposed in advance of said body, and carrier-members integrally joined to said 35 label-gripper member and to said body, said gripper-member being normally spaced in work-receiving position slightly away from said platen, said carrier members being arranged for engagement by a resilient element 40 of said machine, whereby to press said gripper-member firmly against said platen.

2. In a typewriting machine having a platen and lower feed-rolls, a holder for a work-piece arranged for attachment to or 45 detachment from said platen and having a body curved to yieldingly clasp the same without exterior means, and provided with an integral movable part arranged for engagement with said lower feed-rolls to be 50 pressed thereby against said platen for gripping said work-piece.

3. A label-holder for a typewriting machine platen including a flexible sheet-metal body curved to be sprung around said platen, 55 an offset label-gripping member integral with said body, carrier-members integrally joined to said label-gripping member and flexibly joined to said body, tongues separated from the gripping member and from the carrier-members by U-shaped piercings

in said body, and stiffening ribs struck up from each carrier-member to project above said body and be compressed during a rotary movement of the platen to bring the label-gripping member against the platen.

4. A label-holder for a typewriting machine platen including a flexible sheet-metal body curved to be sprung around said platen, an offset label-gripping member integral with said body, carrier-members integrally joined to said label-gripping member and flexibly joined to said body, tongues separated from the gripping member and from the carrier-members by U-shaped piercings in said body, and stiffening ribs struck up from each carrier-member to project above said body and be compressed during a rotary movement of the platen to bring the label-gripping member against the platen, 70 each rib beginning at the forward end of its carrier-member and extending lengthwise thereof, and terminating adjacent the junction of said member with said flexible body, whereby to stiffen said member throughout its length while leaving it free to be swung about its 75 flexible junction with said body.

5. In a typewriting machine, the combination with a platen and lower feed-rolls, of a holder for a work-piece including a platen-clasping part, and a work-piece-gripping part flexibly connected to said platen-clasping member and disposed forwardly beyond the same, the forward end of said gripping part being disposed slightly away from said platen when said holder is in work-receiving position, and the rear end of said gripping part arranged for engagement by said feed-rolls for pressing said forward end against said work-piece when said platen is rotated to bring said work-piece to typing 80 position.

6. In a typewriting machine, the combination with a platen and platen-fed rollers, of a holder for a work-piece including a platen-clasping body-portion having a row 85 of fingers spaced away from each other and formed to clamp around said platen, a work-piece-gripping part disposed in advance of the forward ends of said fingers, bars intermediate said fingers and integral with said 90 gripping part, stiffening beads for each bar, each bar extending downwardly to be flexibly integral with said body-portion, said gripping part being resiliently disposed away from said platen for a work-receiving 95 position, and beads integrally formed in the forward ends of said fingers for increasing the thickness of the fingers as stop-means for the leading edge of the work-piece inserted between said gripping part and said platen, 100 said rollers engaging the beads of the bars to depress the gripping part to clamp the work-piece to the platen.

7. In a typewriting machine, the combination with a platen and lower feed-rolls,

of a holder for a work-piece arranged for attachment to and detachment from said platen, said holder having a body-part curved for clasping said platen, a lateral member forwardly disposed from said body-part and normally positioned slightly away from said platen, said member being movable toward said platen for gripping a work-piece thereagainst, and members integrally and 10 flexibly joined to said body-part and extending forwardly therefrom for carrying said work-gripping member, said carrying members being arranged to be pressed toward said platen by said lower feed-rolls for bringing 15 said movable member into engagement with said work-piece when the latter is in typing position.

8. In a typewriting machine, the combination with a platen and lower feed-rolls, of 20 a holder for a work-piece arranged for attachment to and detachment from said platen, said holder having a part curved for grasping said platen and a part made effective by the pressure of said feed-rolls for 25 gripping said work-piece against said platen.

9. In a typewriting machine, the combination with a platen and lower feed-rolls, of 20 a holder for a work-piece arranged for attachment to and detachment from said platen, said holder having a part curved for grasping said platen and a part whose upper portion is arranged for gripping a work-piece against said platen and whose lower 33 portion is arranged for engagement with said feed-rolls so as to make the pressure of said feed-rolls effective for pressing said upper portion against said platen.
